UNITED STATES PATENT OFFICE.

JOHN J. FORD, OF OTTUMWA, IOWA.

CARD GAME.

1,107,417.

Specification of Letters Patent. Patented Aug. 18, 1914.

Application filed March 29, 1913. Serial No. 757,629.

To all whom it may concern:

Be it known that I, JOHN J. FORD, a citizen of the United States, residing at Ottumwa, in the county of Wapello and State 5 of Iowa, have invented certain new and useful Improvements in Card Games, of which the following is a specification, reference being had to the accompanying drawings.

This invention relates to new and useful 10 improvements in card games and more particularly to a card game for spelling words and the primary object of the invention is to provide a game which will be interesting and amusing to both young and old.

15 A further object of the invention resides in providing a card game, the cards of which have letters of the alphabet inscribed thereon and certain of the cards of which, in addition to the letters referred to, have 20 also inscribed thereon other letters of the alphabet forming words.

With these and other objects in view, the invention consists in the novel features of construction, combination and arrangement 25 of parts as will be hereinafter referred to and more particularly pointed out in the specification and claims.

In the accompanying drawing

Figure 1 is a plan view of one of the lead 30 cards having the word inscribed thereon. Figs. 2 to 6 inclusive are similar views of other cards in the deck which, together with the card shown in Fig. 1, form a word.

In describing my invention, I shall refer 35 to the drawing in which similar reference characters designate corresponding parts throughout the several views and in which 1 indicates a card of any preferred size having inscribed on the face thereof the name 40 of a city of importance, the initial letter of the name being preferably larger than the others. This card, for convenience, with regard to the playing rules may be termed a "lead" card and, in diagonally opposite 45 corners of this card are pips consisting of the first letter of the word which is inscribed on the face thereof. In the present instance, the word inscribed on said card is the name "Boston" and the letter in each of the diagonal 50 corners is the letter "B," but it will be understood that other names may be used and in playing the game, cards with other names thereon are provided, this being only a showing of the type of card used.

55 In Fig. 2, I have shown a card having inscribed on the face thereof, and considerably enlarged, the second letter of the word contained on the "lead" card 1, the same being in the present instance, the letter "O" and in the two diagonal corners are pips 60 consisting of the letter "O." In Figs. 3, 4, 5 and 6, I have shown cards, each of which has inscribed, on the face thereof, a letter of the word contained on the "lead" card, the diagonal corners thereof being also provided 65 with these letters, as described in connection with the cards in Figs. 1 and 2 and the letters of the cards shown in Figs. 2 to 6 inclusive, together with the capital letter of the "lead" card will spell the name of the 70 city contained on the face of said "lead" card. The cards shown in Figs. 3 to 6 inclusive, have respectively inscribed thereon the letters "S," "T," "O," and "N."

The game consists of a deck of seventy- 75 two cards, ten of which have inscribed on the face thereof respectively the names of ten leading cities of the United States, the first letter of the name being capitalized and the name being inscribed in a manner similar 80 to that shown in the card indicated in Fig. 1. The remaining sixty-two cards have inscribed thereon letters of the alphabet containing both consonants and vowels, the same being printed as indicated in the cards 85 shown in Figs. 2 to 6 inclusive and the inscriptions on these cards are such as when properly brought together, with the ten "lead" cards, will spell the names of the 90 ten cities contained on said "lead" cards. 90

In playing the game, the cards are properly shuffled and dealt, one at a time, to the various players, of which there may be from three to nine, as desired. When five or seven persons are playing the game, two 95 of the cards may be removed so that there will be an even number of cards dealt to each player. When the cards have been dealt, the player to the left of the dealer, has the first opportunity to play, by placing in the 100 center of the table or board, a "lead" card. If the first player to the left of the dealer has no such card, in his hand, he passes up this opportunity to make the initial play to the player on his left. The first player to 105 the left of the dealer having such a "lead" card in his hand plays the same and the player next on his left continues the play by placing on the board or table, next to the "lead" card the second letter of the name 110 contained on the "lead" card. Of course, if he has no such card containing this letter, he loses his opportunity to play. Each player plays one card and the player who places on the board the last card of the name contained on the "lead" card, is given the 5 opportunity to play from his hand, a second "lead" card. Of course, if he has no such card in his hand, the opportunity is passed to the next player and so on until such card is found in a player's hand. The 10 object of the game is, of course, to play all the cards from one's hand and the first player who has been relieved of all his cards, by playing the same on the table, in the usual manner, is considered the winner of 15 the game.

From the foregoing, the rules for and the manner of playing the game will be readily understood and it will be seen that I have provided a card game which is interesting 20 and amusing for both young and old. It will also be seen that the rules for playing the game are simple so that the knowledge thereof may be quickly and readily acquired.

As stated above, when five or seven play- 25 ers desire to play this game, two of the cards of the deck are removed, in order that an even number of said cards may be distributed to each player. In removing such cards from the deck, the two are taken which 30 would not cripple the deck to such an extent as would prevent the formation of the name of the city, in connection with which the same are adapted to be used. For instance, assuming that Washington, D. C., is one of the ten cities, the names of which are to be 35 formed in the playing of this game, the letters "D. C." would be removed from the deck which, obviously, would permit the formation of the name Washington in the 40 playing of the game.

Having thus described this invention, what is claimed is:—

1. A deck of playing cards comprising a plurality of sets of cards, a head card for each set displaying a word, and the remaining cards of the set displaying each one of the letters of the head card word with the exception of the initial letter thereof. 45

2. A deck of playing cards comprising a plurality of sets of cards, a head card for each set displaying a word and bearing the significance of the initial letter of the word, the remaining cards each bearing the significance of one of the remaining letters of the word and pips carried by the card to indicate the letter which it signifies. 50 55

In testimony whereof I hereunto affix my signature in the presence of two witnesses.

JOHN J. FORD.
